(57) CLAIM

The ornamental design for a handbag, as shown and described.

DESCRIPTION

FIGS. 1-7 show a handbag showing my design in a first configuration and FIGS. 8-14 show the handbag showing my design in a second configuration; and wherein

FIG. 1 is a front perspective view of the handbag in the first configuration;

FIG. 2 is a front elevational view of the handbag of FIG. 1;

FIG. 3 is a rear elevational view of the handbag of FIG. 1;

FIG. 4 is an elevational right side view of the handbag of FIG. 1;

FIG. 5 is an elevational left side view of the handbag of FIG. 1;

FIG. 6 is a bottom plan view of the handbag of FIG. 1;

FIG. 7 is a top plan view of the handbag of FIG. 1;

FIG. 8 is a front perspective view of the handbag in an expanded position;

FIG. 9 is a front elevational view of the handbag of FIG. 8;

FIG. 10 is a rear elevational view of the handbag of FIG. 8;

FIG. 11 is an elevational right side view of the handbag of FIG. 8;

FIG. 12 is an elevational left side view of the handbag of FIG. 8;

FIG. 13 is a bottom plan view of the handbag of FIG. 8; and, FIG. 14 is a top plan view of the handbag of FIG. 8.

The broken lines are included for the purpose of illustrating portions of the handbag that form no part of the claimed design.
